(57) **CLAIM**

The ornamental design for a warehouse robot, as shown and described.

DESCRIPTION

FIG. 1 is a front perspective view a warehouse robot showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

No bottom plan view is included because the bottom of the warehouse robot will not be visible in use.

The broken lines in the figures illustrate portions of the warehouse robot that form no part of the claimed design.
